(57) **CLAIM**

The ornamental design for a film dispenser for use with coreless film roll, as shown and described.

DESCRIPTION

FIG. 1 is a perspective view of a film dispenser for use with a coreless film roll showing our new design in use;

FIG. 2 is the perspective view of FIG. 1 without environmental subject matter;

FIG. 3 is a front elevation view thereof, the top plan and bottom plan views being identical thereto;

FIG. 4 is a rear elevation view thereof;

FIG. 5 is an enlarged right side elevation view thereof, the left side elevation view being identical thereto;

FIG. 6 is a perspective view of the dispenser in a first engaged configuration;

FIG. 7 is a perspective view of the dispenser in a second engaged configuration;

FIG. 8 is a perspective view of the female dispenser member of the film dispenser shown separately for clarity;

FIG. 9 is a front elevation view thereof, the top plan and bottom plan views being identical thereto;

FIG. 10 is a rear elevation view thereof;

FIG. 11 is a right side elevation view thereof;

FIG. 12 is a left side elevation view thereof;

FIG. 13 is a perspective view of the male dispenser member of the film dispenser shown separately for clarity;

FIG. 14 is a front elevation view thereof, the top plan and bottom plan views being identical thereto;

FIG. 15 is a rear elevation view thereof;

FIG. 16 is a right side elevation view thereof;

FIG. 17 is a left side elevation view thereof; and,

FIG. 18 is an opposite perspective view thereof.

Broken lines in a dot-dash pattern indicate boundary lines between claimed subject matter and unclaimed subject matter.

Broken lines in a dash-dash pattern indicate elements that form no part of the claimed design.
